UNITED STATES PATENT OFFICE

145,931

DESIGN FOR A SUNDIAL

Ciro Americo Fiorio, Northfield, Ill.

Application December 13, 1945, Serial No. 124,682

Term of patent 7 years

(Cl. D42—7)

To all whom it may concern:

Be it known that I, Ciro Americo Fiorio, a citizen of the United States, residing at Northfield, in the county of Cook and State of Illinois, have invented a new, original, and ornamental Design for a Sun Dial, of which the following is a specification, reference being had to the accompanying drawing, forming part thereof.

Figure 1 is a view in side elevation of a sun dial showing my new design;

Figure 2 is a plan view of the sun dial, and Figure 3 is a sectional view of the sun dial taken near the bottom thereof in order to show the base in plan view and to show the spacing of the standards that support the bowl.

I claim:

The ornamental design for a sun dial, as shown.

CIRO AMERICO FIORIO.
